UNITED STATES PATENT OFFICE.

LORENZO NORWOOD ANDERSON, OF HAWKINSVILLE, GEORGIA.

SELF-SERVING STORE.

Application filed February 14, 1921. Serial No. 444,687.

To all whom it may concern:

Be it known that I, LORENZO NORWOOD ANDERSON, a citizen of the United States, residing at Hawkinsville, in the county of Pulaski and State of Georgia, have invented certain new and useful Improvements in Self-Serving Stores, of which the following is a specification.

This invention relates to self-serving stores so constructed that the customers, in passing through the store, are compelled to follow a definite path and select from the various shelves and bins the goods which they desire to purchase, and the object of my invention is to provide means, in such a store, for displaying a maximum quantity of goods to the best advantage, and to provide means whereby the checkers or attendants of the store may at all times have the shelves and bins in view and may keep watch of the customers as they pass through the store. Other objects of my invention are to economize space without limiting the display of goods or the paths traversed by the customers from one part of the store to the other.

In carrying out my invention I provide a store front with glass windows arranged in front of display shelves for different kinds of goods, and in the middle of the front wall I provide an entrance having doors opening into a lobby screened on opposite sides and having at its inner end gates opening into the store proper and arranged in front of basket bins or shelves, which latter are located immediately in front of checkers' stands or desks which are arranged in front of an aisle running crosswise of the store on the opposite side of which is a checker's stand located at the front end of two rows of shelves between which there is a space for the clerks and at the rear end of which is provided an ice-box or similar receptacle. The side walls of the lobby on the inside of the store are provided with shelves and bins, and shelves and bins are provided on the side walls of the front portion of the store on opposite sides of the lobby. These shelves and bins connect on each side with a row of zig-zag shelves extending to the rear part of the store. These zig-zag shelves are an important feature of my invention as in this way the area of the shelves in a given length of store space is materially increased and the arrangement is

also such that they are brought within the vision of the checkers at different parts of the store. There is a supply or storage room in the back part of the store having doors for closing it. In this way a large quantity of goods may be displayed not only to the customers as they pass through the store but to the checkers who watch the customers while inspecting and carrying away the goods and purchasers cannot leave the store without passing through a gate guarded by checkers.

In the accompanying drawings:—

Figure 1 is a plan view of a self-serving store embodying my improvements. 70

Figure 2 shows a section on the line 2—2 of Figure 1.

Figure 3 shows a section on the line 3—3 of Figure 1.

Figure 4 is a section on the line 4—4 of 75 the same figure.

Figure 5 is a detail view of a part of the shelving.

The store as a whole is contained within the area bounded by the walls 1, 2, 3, 4. The front wall is provided with plate glass windows A, in rear of which, within the store, are display shelves or bins a, these shelves or bins being divided as indicated at a' so that shelves a² are provided on the inside in order 80 that customers may obtain goods from them. The front doors B open into a narrow lobby C on opposite sides of which there are low panelled walls c over which are arranged screens c' extending to a height some distance from the parts c. These screens prevent customers from reaching over into the interior of the store while passing through the lobby. Inside the walls of the lobby there are shelves D for display of goods. 90 The screens c' may be braced by cross bars c². 95

Basket bins E, E' are arranged in rear of the lobby and between these bins and the rear ends of the walls c are mounted turnstile gates F, F' opening in one direction, that is, 100 inwards only. These gates are located in front of checkers' stands G, G'. The side walls 2 and 4 at the front of the store on opposite sides of the lobby are provided with shelves H and bins h and each row of shelves 105 communicates with a zig-zag row of shelves K, K' extending to the rear portion of the store. Each set of shelves K, K' connects at its rear end with shelves L and the shelves L connect with diagonally arranged shelves 110

M having a door N opening into a supply room O. The shelves and bins may be of any desired construction and may be equipped with wire netting P, when desired, 5 for ventilating purposes.

As shown in Fig. 5 the shelves at K' are not as high as at K leaving an opening with storage spaces K².

Between the back door N and the checkers' stands G, G' there are longitudinally arranged shelves or bins Q spaced apart and connected at the rear by a receptacle R which may serve as an ice-box or refrigerator. In front of the shelves Q there is a 10 checker's stand S, provided with shelves S', entrance ports T being provided, as shown, closed by chains or ropes t.

It will be observed that the checkers' stands G, G' and the basket stands are separated so as to provide a passageway U leading out to the lobby. A turnstile gate E² is located between the bins E, E', opening outwards only, so that customers in leaving the store are compelled to pass between the 15 checkers G, G'. A portion of the basket bin E is covered, as shown, so that customers cannot take baskets when leaving the store and the turnstile or gate E² is also covered, as shown, so that customers are compelled to 20 turn the gate in one direction only.

Customers passing the store can observe goods attractively displayed in the shelves or bins in rear of the glass panels A. When they enter the store they are compelled to 25 pass in one direction or the other through the gates F, F' and can be seen by the checkers located at G or G'. They can supply themselves with baskets and then enter the compartments W where some of the goods 30 are displayed and where they can obtain such goods, so displayed, as they desire. They can then pass rearwards and inspect and obtain goods from the shelves K, L and M and also from the ice-box R or from the 35 shelves or bins Q and S'. Having thus passed through the store and obtained supplies of goods they cannot leave without passing through the narrow passage U close to the checkers and then out through the 40 gate E². If they can enter the store through the gates E, F' they cannot leave without passing again through the passage U and gate E².

Not only is a large area provided for the 45 display of goods, but the customers can be watched closely by the checkers. For instance, the checkers at G and G' can at all times, or whenever desired, watch customers when in the compartments W. When the 50 customers pass into the rear portion of the store the checker at G or G' can watch them and can also see most of the shelf space in the row of shelves K. The checker at G', looking diagonally across the store, can see 55 practically all of the shelf space K on one

side. At any rate, he can see the customer as he passes into any of the spaces bounded by the zig-zag row of shelves. Both checkers at G, G' can have the shelves L and M at all times in full view. In like manner the 70 checkers at S can readily watch the customers in the compartments W and can also watch the collection of goods by the customers when passing the zig-zag shelves and the other shelves at the rear of the store.

It will be understood that cash registers, weighing scales and the like may be suitably located; such devices are indicated at G² in the drawings. It will also be understood that some features of the invention may be used without the others and that such devices as are often employed in such stores 75 may be added.

I claim as my invention:

1. A self-serving store having a glass front with display shelves in rear thereof, and provided with a lobby bounded by side walls having screens above them and shelves on the inner sides within the store below the screens, shelves on the front and side walls 80 of the front part of the store upon opposite sides of the lobby, shelves in the rear portion of the store, checkers' stands in rear of the lobby facing the shelves in the store on opposite sides of the lobby and accessible 85 from opposite sides of the store, and entrance and exit gates from the lobby to the opposite sides of the store and from the store to the lobby between the checkers' stands.

2. A self-serving store having at the front a lobby and having within it shelf spaces on opposite sides of the lobby within the store, checkers' stands in rear of the lobby facing the shelves in the front part of the 105 store and having an exit aisle between the checkers' stands, an exit gate controlling said aisle, entrance gates controlling passage-ways between the lobby and the opposite sides of the store, shelves arranged 110 in zig-zag fashion on opposite sides in the middle part of the store extending from front to rear thereof within view of the checkers, and counters extending centrally from a point adjacent the checkers' 115 stands throughout the greater portion of the length of the store room and having an aisle formed therebetween, said counters thereby providing passageways along the zig-zagged shelves.

3. A self-serving store having at the front a lobby and at its front portion shelves on opposite sides of the lobby, shelves arranged in zig-zag fashion running along the side walls of the store from front to rear 120 thereof, entrance and exit gates for the lobby, checkers' stands adjacent said gates but in rear thereof, shelves arranged in the middle portion of the rear part of the store, and another checker's stand arranged be- 125 130

tween said last-mentioned shelves and the first-mentioned checkers, said checkers' stands being accessible from either side of the store.

- 5 4. A store having front, side and rear walls, the front having transparent portions therein, an entrance and exit centrally located in the front wall, a lobby with which the entrance communicates formed between 10 parallelly extending partitions which extend longitudinally into the store, a checkers' department at the end of the lobby and in the store, a salesroom enclosed by shelves, which salesroom extends to the front of the store at each side of the partitions, said partitions having shelves arranged therealong inside the salesroom, one way passages at each side of the lobby and 15 adjacent the checkers' department and permitting entrance to the salesroom only, an exit from the salesroom comprising an aisle extending through the checkers' department and terminating in said lobby between 20 the entrance passages, and having a gate permitting of exit only from the salesroom, said exit aisle being accessible from either side of the salesroom, the shelves at the front 25 of the salesroom extending along the transparent front of the store and having display shelves next the front inaccessible to customers and having other shelves to the rear of the display shelves and in the sales department from which a customer may select goods, all parts of said salesroom being 30 visible to persons at the checking stand.
5. A store having front, side and rear walls, the front having transparent portions therein, a passageway in the front wall forming a combined entrance and exit, a

lobby with which the passageway communicates formed between parallel partitions which extend longitudinally into the store, a checkers' department at the end of the lobby and in the store, a salesroom enclosed 35 by shelves, which salesroom extends to the front of the store at each side of the partitions, said partitions having shelves arranged therealong inside the salesroom, one way passages at each side of the lobby and 40 adjacent the checkers' department and permitting entrance to the salesroom only, an exit from the salesroom comprising an aisle extending through the checkers' department and terminating in said lobby between 45 the entrance passages, and having a gate permitting of exit only from the salesroom, said exit aisle being accessible from either side of the salesroom, the shelves at the front 50 of the salesroom extending along the transparent front of the store and having display shelves next the front inaccessible to customers and having other shelves to the rear of the display shelves and in the sales department from which a customer may select goods, all parts of said salesroom being 55 visible to persons at the checking stand.

In testimony whereof, I have hereunto subscribed my name.

LORENZO NORWOOD ANDERSON.
